[57]

ABSTRACT

Brush for electric machines, comprising a brush body made of carbon, current-carrying fittings, and a spring insulated from the brush body and serving to press the latter against the fittings. The spring may be a flat or a spiral spring; in the latter case a separate pressure element may be interposed.

FIG. 1

FIG. 2

FIG. 3

FIG. 4

BRUSH FOR ELECTRIC MACHINES

The present invention relates to electric machines and more specifically to brushes for electric machines.

Known in the art are brushes for electric machines, which comprise a brush body proper, a carbon or graphite rod, and current-carrying fittings with a current-bearing wire affixed thereto.

Also known in the art is a brush (cf., USSR Inventor's certificate No. 208100) with split current-carrying fittings, wherein the latter are secured to the brush by a bolt passing through a hole made in the brush.

This kind of attachment has the following disadvantages: liability to loosening of the bolt connection during vibration of the brush, resulting in worsening of the electrical and thermal contact between the brush and the fittings, and also inconvenient mounting and dismantling of the brush due to the necessity of locking the bolt in the tightened condition.

Another brush is known in the art (cf. French patent No. 1469006). Herein, the current-carrying fittings are not secured to the brush, but only pressed to it in the course of operation by means of a spring, which latter simultaneously presses the brush against the surface of the rotor. These brushes can be employed for relatively light currents, because the pressure exerted on the brush for its pressing against the rotating surface is relatively light, 0.1-0.2 kg/cm², and therefore not able to effect a reliable contact between the fittings and the brush at heavy currents. Beside that, the fact that the brush is not secured to the fixtures creates a substantial inconvenience in installing and removing the brush from the brush holder.

It is therefore a general object of the invention to obviate the disadvantages inherent in the above described prior-art brushes for electric machines.

It is a specific object of the invention to provide a brush for electric machines with a split attachment of current-carrying fittings, providing for a reliable electrical and thermal contact between said fittings and the brush body proper, and also permitting convenient and quick assembly of the brush with the fittings and allowing the latter to be used repeatedly.

These and other objects are achieved by the provision of a brush for electric machines, comprising current-carrying fittings attached to the brush body by means of a spring, wherein the brush is so formed, according to the invention, that one end of the spring is secured to the current-carrying fittings, whereas the other end preferably carries a pressure element secured thereto, while the brush body, due to the action of the spring, is pressed between the current-carrying fittings and the pressure element, at least the brush spring being insulated from the brush body.

It is expedient that an open through slot is made in the brush body, and a spirally threaded hole is made in the current-carrying fittings along the axis of the slot, a screw is screwed into said latter hole from the outside to release the spring.

The spring which presses the brush body between the current-carrying fittings and the pressure element can be made in the form of a coil tension spring positioned in the brush slot.

It is however contemplated by the invention that the above mentioned spring takes the form of a flat spring whose one end is combined with the pressure element.

In order that the invention may be more clearly understood actual, exemplary embodiments of a brush for electric machine will now be fully described with reference to the accompanying drawings, of which:

5 FIG. 1 is a longitudinal section of a first exemplary form of a brush for electric machines, according to the invention;

FIG. 2 is a side view of the same, partly sectionalized;

10 FIG. 3 is a longitudinal section of another exemplary form of a brush for electric machines, according to the invention; and

FIG. 4 is a side view of the same, partly sectionalized.

15 Referring now to FIGS. 1 and 2, an exemplary brush for electric machines is shown, comprising current-carrying fittings 2 attached to a graphite body 3 of a brush 1 by means of a coil latter 4. The spring is screwed with one end into a threaded hole 5 made in the current-carrying fittings 2, whereas the other end of the spring 4 is applied onto a screw 6 which performs 20 the function of a pressure element. The spring 4 presses the body 3 of the brush 1 between the current-carrying fittings 2 and the head of the screw 6.

25 To avoid heating of the coil spring 4 by the electric current, the spring is insulated from the brush 1 by means of a washer 7 and a pipe 8, both made of an insulating material, the spring 4 being inclosed in said pipe.

30 For more convenient mounting and fixing the position of the current-carrying fittings 2, a through slot 9 is made in the graphite body 3 of the brush 1, which slot accommodates the coil spring 4.

35 In another embodiment of the brush 1 for electric machines (FIGS. 3, 4), the graphite body 3 of the brush 1 is pressed between the current-carrying fittings 2 and a flat spring 10 which is secured to said fittings and carries a pressure element 11 secured to its end. Slots 12 are made in the graphite body 3 of the brush 1 to fix in position the current-carrying fittings 2 and the free end of the spring 10.

40 In this brush 1, the pressure element takes the shape of a strip made of an insulating material, with the aim of preventing electric current flow through the flat spring 10 to preclude heating thereof. Convenient handling of the graphite body 3 of the brush 1 is effected by a specially provided fixture (not shown) having a spirally threaded working part.

45 In the first form of the brush for electric machines, illustrated in FIGS. 1, 2, wherein the coil spring 4 is employed, the fixture is screwed into the hole 5 in the current-carrying fittings and into the spring 4, thus extending the latter upon which the body 3 of the brush 1 can easily be removed and replaced with another one, if necessary.

50 In the second brush form, illustrated in FIGS. 3, 4, wherein the flat spring 10 is employed, the fixture is screwed into the hole 5 and presses off the flat spring 10, thus releasing the body 3 of the brush 1.

55 The above disclosed brushes for electric machines provide for a simple and reliable fastening of the brush and also for easy replacement of the graphite body of the brush.

60 What is claimed is:

1. A brush for electric machines to provide electric contact with a moving part of a machine, comprising a brush body made of carbon and having an open through slot; current-carrying fittings on said body and having therein a threaded opening; and a spiral tension spring located in said slot, one end of said spring being

fixed in said threaded opening, while the other end of said spring is applied onto a pressure element; said spring and said pressure element being insulated from said brush body, the latter being held tightly between said fittings and said pressure element.

2. A brush for electric machines to provide electric contact with a moving part of a machine, comprising a

brush body made of carbon; current-carrying fittings; and a flat spring, one end of the latter being attached to said fittings; and spring being insulated from said brush body, the latter being held between said fittings and the free end of said spring.
